(57) **CLAIM**

The ornamental design for a bracelet, as shown and described.

DESCRIPTION

FIG. 1 is a front-top-left perspective view of a first embodiment of a bracelet, showing my new design;
FIG. 2 is a front-bottom-left perspective view thereof;
FIG. 3 is a front elevation view thereof;
FIG. 4 is rear elevation view thereof;
FIG. 5 is a left side elevation view thereof;
FIG. 6 is a right side elevation view thereof;
FIG. 7 is a top plan view thereof;
FIG. 8 is a bottom plan view thereof;
FIG. 9 is a front-top-left perspective view of a second embodiment of a bracelet, showing my new design;
FIG. 10 is a front-bottom-left perspective view thereof;
FIG. 11 is a front elevation view thereof;
FIG. 12 is rear elevation view thereof;
FIG. 13 is a left side elevation view thereof;
FIG. 14 is a right side elevation view thereof;
FIG. 15 is a top plan view thereof;
FIG. 16 is a bottom plan view thereof;
FIG. 17 is a front-top-left perspective view of a third embodiment of a bracelet, showing my new design;
FIG. 18 is a front-bottom-left perspective view thereof;
FIG. 19 is a front elevation view thereof;
FIG. 20 is rear elevation view thereof;
FIG. 21 is a left side elevation view thereof;
FIG. 22 is a right side elevation view thereof;
FIG. 23 is a top plan view thereof; and,
FIG. 24 is a bottom plan view thereof.

The evenly-spaced dashed lines in the figures illustrate portions of the bracelet that form no part of the claimed design. The long dash-short dash lines represent an unclaimed boundary of the claimed design.

1 Claim, 18 Drawing Sheets
